(57) **CLAIM**

The ornamental design for a housing for the installation of electrical and electronic components, as shown and described.

DESCRIPTION

FIG. 1 is a front perspective view of a housing for the installation of electrical and electronic components, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The area in white encased by coarse dotted lines, in FIGS. 1 and 2, illustrate portions of the housing for the installation of electrical and electronic components, which form no part of the claimed design.
